(57) **CLAIM**

The ornamental design for an electrical cable connector, as shown and described.

DESCRIPTION

FIG. 1 is a front, right side and top perspective view of an electrical cable connector showing my new design;

FIG. 2 is a front, right side and top exploded perspective view thereof;

FIG. 3 is a front, right side and bottom perspective view thereof;

FIG. 4 is a front, right side and bottom exploded perspective view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof; and,

FIG. 10 is a bottom plan view thereof.

The broken line portion of the figure drawings is included to show unclaimed subject matter only and forms no part of the claimed design.
